UNITED STATES PATENT OFFICE.

JONAS NORTHROP, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

SPECIFICATION forming part of Letters Patent No. 691,481, dated January 21, 1902.

Application filed July 8, 1901. Serial No. 67,436. (No model.)

To all whom it may concern:

Be it known that I, JONAS NORTHROP, a subject of the King of Great Britain, residing at Hopedale, county of Worcester, State of Massachusetts, have invented an Improvement in Automatic Filling-Replenishing Looms, of which the following description, in connection with the accompanying drawings, is a specification, like characters on the drawings representing like parts.

In looms furnished with mechanism for effecting a change of filling upon breakage or running out of the same, as distinguished from looms wherein the filling is changed or replenished prior to complete exhaustion of the filling in the shuttle in play, the construction is such that if the filling fails either by breakage or exhaustion while it is being laid in one direction—viz., toward the replenishing mechanism—two additional blank or empty picks will be made before the fresh filling is provided. Supposing that this occurs on half the number of filling failures, a fault is made in the cloth each time, and if the failure occurs when the filling is laid in the other direction ordinarily but one pick will be bare of filling before the fresh supply can be provided.

My present invention has for its object the production of a loom wherein the formation of faults in the cloth, as above mentioned, will be obviated and the number of blank picks reduced to a minimum, thereby improving the quality of the cloth accordingly.

My invention may be used in connection with mechanism to automatically provide the shuttle with a fresh supply of filling in place of the spent supply or with mechanism wherein a fresh or full shuttle is provided when necessary to take the place of the spent or empty one, as will be manifest hereinafter; but herein I have shown and described one practical embodiment of my invention in connection with replenishing mechanism of the former type.

Figure 1 represents a transverse section of a sufficient portion of a loom to be understood, taken at right angles to the axis of the filling-feeder between the end plates or heads thereof. Fig. 2 is a top or plan view of the lay and shuttle-box at the replenishing side

of the loom, with the shuttle in the box, and also illustrating the detector for indicating non-continuity of the filling when laid, the replenishing mechanism above the line xx , Fig. 55 1, being omitted; and Fig. 3 is a side elevation of the detector in normal position, the lay and shuttle-box being shown in section.

The lay A^3 , slotted at 10, below the shuttle-box B^X , to permit the ejection of the spent 60 filling-carrier from the self-threading shuttle S by the entrance thereto of a fresh filling-carrier, the filling-feeder F , rotatable on a fixed horizontal axis a and adapted to carry a plurality of filling-carriers b , to be transferred one by one to the shuttle by the transerrer f' , fulcrumed at f on the stand A^7 , which supports the feeder F , the fixed stop h' for the leading filling-carrier of the series, the ratchet a^8 , and a dog f^{10} , pivoted on the 70 transerrer at f^{12} and provided with a tooth f^{13} to operate with the ratchet and intermittently rotate the feeder in the direction of arrow 36, Fig. 1, when the transerrer is returned to the position shown by the action 75 of a strong spring S^X after transfer of a filling-carrier to the shuttle, may be and are all substantially as in United States Patent No. 664,790, dated December 25, 1900, like parts being correspondingly lettered herein. 80 The transerrer is herein shown as having rigidly connected with it an arm f^8 , depending below the fulcrum f and provided at its lower end with an inturned notched dog f^{30} , which when engaged by an actuating-bunter, 85 to be described, swings the arm f^8 in direction of arrow 30 to depress the transerrer and effect a change of filling, substantially as in the patent referred to. Herein the filling-replenishing mechanism is shown as located at the right-hand side of the loom to provide the instrumentality for laying the filling with a fresh supply of filling when the latter fails, the shuttle being in the shuttle-box B^X at the adjacent end of the lay. Referring to Figs. 1 and 2, brackets b^2 on the lay near said shuttle-box form bearing for a rock-shaft b^3 , having fast upon it a bunter b^4 , movable in a vertical plane passing through the dog f^{30} , said shaft having secured to it 90 near its inner end a collar b^5 , provided with a finger b^6 , the collar and the hub of the

bunter preventing longitudinal movement of the rock-shaft. A second collar b^7 , fast on the latter, is provided with a projection or stop b^8 , and one end of a spring s^x , coiled about the shaft, Fig. 2, is secured to the collar, the other end being suitably fixed, as by the bearing b^2 , the winding of the spring being such that the stop is normally held against the bottom plate 6 of the shuttle-box with the bunter out of the path of the dog f^{30} and the finger b^6 upturned. It will be manifest that whenever the forward end of the bunter is raised high enough the replenishing mechanism will be actuated on the forward beat of the lay to complete a change of filling when the lay is fully forward. Manifestly with the construction herein illustrated such change must be effected only when the shuttle is in the adjacent shuttle-box B^x , as it will be on the pick which thus boxes the shuttle, and if a failure of filling is detected on that same pick and the bunter be through such detection moved into operative position then the change of filling will be effected on the same pick without any lost pick. One means for effecting such result will now be described as a practical embodiment of this part of my invention.

A stand m^x , having a longitudinal guide-way therein, is secured to the breast-beam A^{40} transversely thereto nearly opposite the inner end of the shuttle-box B^x , as shown in Fig. 2, to support a slide-bar M , having at its inner end a filling detector or fork M^x , fulcrumed at m and adapted to at times engage and be tilted by the laid filling when the lay beats up.

Referring to Fig. 1, a bell-crank $N N'$ is fulcrumed at N^x on the lower part of the loom-frame, the arm N' having a follower N^2 , which travels on a cam C^x , fast on the cam-shaft C and so shaped as to effect inward movement of the upper end of the upturned arm N at every other pick. The upper end of said arm N is extended through a longitudinal opening m' in the stand, Fig. 2, between two cross bars or lugs $5 5$ on the slide M , so that whenever the arm N is rocked to the rear the slide will be moved to bring the detector M^x into position to detect continuous or non-continuous filling on the forward beat of the lay. On the side of the slide I have shown a positioning device for the bunter, consisting of a lever p , fulcrumed at p^x and having at its outer end a lateral lug p' to at times engage the finger b^6 and rock the bunter-shaft on the forward beat of the lay. The inner end of the lever p extends beneath a bent leg m^2 , secured to or forming a part of the fulcrum m of the detector M^x , and the normal relative position of the parts is shown in Fig. 3. If now the detector being moved into detecting position, the lay beats up, the filling, if properly laid, will tilt the detector, depressing the leg m^2 and the adjacent end of lever p , elevating its outer end, so that the lug p' will be above the path of the finger b^6 ,

and no change in the normal inoperative position of the bunter b^4 will be effected. Should the filling fail, however, its non-continuity will result in leaving the detector M^x in the position shown, so that the lug p' will meet and turn back the finger b^6 and the bunter will coöperate with the dog f^{30} , and a change of filling will be effected. It will be manifest, therefore, that the filling-replenishing is controlled and its actuation effected, broadly speaking, by or through indicating action of the detector that the filling is non-continuous. Remembering that in the construction herein illustrated the filling can be changed only on boxing of the shuttle at one end of the lay, it will be obvious that the detector should coöperate with the filling on alternate picks, and for this reason the detector is withdrawn into inoperative position on the other picks by or through the cam C^x and the intervening devices.

From the foregoing it will be manifest that the change of filling is effected on the pick on which indicating action of the detector occurs, so that no loss of picks will result, and such indicated pick, it will be noted, is in the present instance that one on which the shuttle travels toward and into the shuttle-box nearest the replenishing mechanism. If the filling fails on the opposite pick, no operation of the detector is effected, nor is it necessary; but on the succeeding pick the indicating action of the detector causes filling-replenishment on such pick and only the one pick will be bare of filling. This may, if necessary or desirable, be provided for by any suitable let-back action of the take-up mechanism, which is so well known as to need no explanation to those skilled in the art, nor does it form any part of my invention.

The fulcrum p^x is laterally extended, Fig. 2, and downturned at its outer end to form a shuttle-feeler p^5 , so located as to sweep over the lay when the latter and the slide M move toward each other, provided the shuttle is properly boxed. If it projects beyond the inner end of the shuttle-box, the feeler p^5 strikes it and is swung toward the front of the loom, elevating the lug p' to prevent operative positioning of the bunter, so that change of filling will be prevented if the shuttle is improperly boxed. A light spring s^{10} may be mounted on the slide to normally hold the lever p and the detector in the position shown to practically counterbalance the tilting action of the shuttle-feeler. A spring S^{10} (see dotted lines, Fig. 1) may, if desired or found necessary, be employed to retain the follower N^2 on the cam C^x , the inward movement of the detector-slide being effected by the combined action of the spring and the weight of the bell-crank $N N'$.

My invention is not restricted to the construction shown and described, for various modifications or changes may be made by those skilled in the art without departing from the spirit and scope thereof.

I believe myself to be the first to devise means for effecting a change of filling in a shuttle upon failure of such filling on the same pick on which such failure is detected, 5 and I have attempted herein to show and describe in detail only one practical mode of carrying out my invention.

Having described my invention, what I claim as new, and desire to secure by Letters 10 Patent, is—

1. In a loom, an instrumentality to lay the filling, means to detect non-continuity of the latter, and mechanism the actuation of which is effected by or through said means, to automatically provide said instrumentality with a fresh supply of filling on the pick on which non-continuity of filling is detected.

2. In a loom, an instrumentality to lay the filling, means independent thereof to detect 20 non-continuity of filling when laid, and mechanism to automatically provide such instrumentality with a fresh supply of filling, said mechanism being controlled and its actuation effected, by or through the detecting means, 25 to supply filling on the pick in which the filling is laid non-continuously.

3. In a loom, an instrumentality to lay the filling, means to detect non-continuity of the latter on alternate picks, and mechanism actuated by or through detecting action of said means, to automatically provide said instrumentality with a fresh supply of filling on the same pick as that on which non-continuity of filling is detected.

35 4. In a loom, an instrumentality to lay the filling, means to periodically detect and indicate non-continuity of the latter, and mechanism in operative condition on corresponding periods, to provide said instrumentality with a fresh supply of filling, said mechanism being controlled and its actuation effected by or through the detecting means upon the detection of non-continuity of the filling.

5. In a loom, a shuttle adapted to contain 45 a supply of filling, a detector to indicate non-continuity of the filling laid by the shuttle, and mechanism actuated by or through indicating action of the detector to automatically provide the shuttle with a fresh supply of filling on that pick on which non-continuity of filling is detected.

6. In a loom, an instrumentality to lay the filling, mechanism, located at one side of the loom, to automatically provide said instrumentality with a fresh supply of filling, and a detector at the same side of the loom, to indicate non-continuity of filling laid, indicating action of the detector when the filling is laid toward said mechanism operating to effect the actuation of the latter on the same pick.

7. In a loom, a shuttle to contain a supply 65 of filling, mechanism located at one side of the loom to automatically provide the shuttle with a fresh supply of filling, and a detector at the same side of the loom, to indicate filling failure, indicatory action of said detector

on the pick of the shuttle toward said mechanism effecting the actuation of the latter to change the shuttle - filling on the indicated 70 pick.

8. In a loom, a shuttle adapted to contain a supply of filling, a detector independent of the shuttle to indicate filling failure, and mechanism controlled and actuated by or 75 through indicating action of said detector to automatically provide the shuttle with a fresh supply of filling on the indicated pick.

9. In a loom, the lay, an instrumentality to lay the filling, mechanism to provide said instrumentality with a fresh supply of filling, normally inoperative actuating means for said mechanism, movable with the lay, and a detector to indicate non-continuity of filling when laid, the actuating means being controlled and rendered operative by or through indicating action of the detector, to effect operation of the said mechanism on the forward beat of the lay immediately succeeding the indicated non-continuous pick of filling. 90

10. In a loom, the lay, a shuttle adapted to contain a supply of filling-replenishing mechanism, normally inoperative actuating means therefor, movable with the lay, and a detector to indicate failure of filling when laid, 95 said actuating means being controlled and rendered operative by or through indicating action of the detector on alternate picks, to effect the actuation of the replenishing mechanism, through the movement of the lay, on 100 the same pick.

11. In a loom, the lay, a shuttle adapted to contain a supply of filling, filling-replenishing mechanism, normally inoperative actuating means therefor, and a detector to operate indicatively indicate filling failure on each pick toward said replenishing mechanism, the actuating means being controlled and rendered operative by or through such operative indication of the detector to actuate the said replenishing mechanism on the same pick. 110

12. In a loom, the lay, a shuttle adapted to contain a supply of filling, filling-replenishing mechanism, a normally inoperative actuating-bunter therefor on the lay, and a detector independent of the shuttle to indicate failure of filling, the bunter being moved into operative position by or through operative indication of filling failure by the detector, to actuate the said replenishing mechanism on the 120 forward beat of the lay immediately succeeding such indication. 115

13. In a loom provided with filling-replenishing mechanism, an instrumentality to lay the filling, a detector to detect and indicate 125 non-continuity of the filling when laid, and means to periodically move the detector into operative position, said mechanism being controlled and its actuation effected by or through indicating action of said detector, due to non-continuity of filling laid, when said detector is in operative position to provide the said instrumentality with fresh filling. 130

14. In a loom provided with filling-replen-

ishing mechanism, an actuating-bunter therefor mounted on the lay, the lay, a shuttle adapted to contain a supply of filling, a detector to indicate failure of the filling, means to move it into operative position on alternate picks, and devices controlled by indicating action of the detector to effect coöperation of the bunter and the replenishing mechanism and thereby provide the shuttle with a fresh supply of filling on the indicated pick.

15. In a loom provided with filling-replenishing mechanism, a normally inoperative actuating-bunter therefor on the lay, the lay, a detector to detect filling failure, and a positioning device for the bunter, controlled by said detector, detection of filling failure by the latter operating to effect coöperation of the positioning device and bunter, to effect through the latter the actuation of the replenishing mechanism to provide the shuttle with a fresh supply of filling.

16. In a loom provided with filling-replenishing mechanism, an actuating-bunter therefor on the lay, the lay, a shuttle to contain a supply of filling, a detector to indicate non-continuity of the filling when laid, means governed by the detector to effect coöperation of the bunter and the replenishing mechanism upon detection of filling failure, and a shuttle-feeler to prevent such coöperation if the shuttle is improperly boxed when the filling failure is detected.

17. In a loom, a shuttle adapted to contain a supply of filling, a detector to indicate non-continuity of the filling laid by the shuttle, mechanism actuated by or through indicating action of the detector to automatically provide the shuttle with a fresh supply of filling on the detected pick, and means to prevent such actuation if the shuttle is improperly boxed on such pick.

18. In a loom provided with filling-replenishing mechanism, an actuating-bunter therefor on the lay, the lay, a shuttle to contain a supply of filling, a detector to indicate non-continuity of the filling when laid, a slide on which the detector is fulcrumed, means

mounted on the slide and governed by the detector to effect coöperation of the bunter upon detection of filling failure, and means to move the slide, and thereby the detector, into operative position on each pick toward the replenishing mechanism, to thereby permit detecting operation of the said detector only on such pick.

19. In a loom provided with filling-replenishing mechanism, an actuating-bunter therefor on the lay, the lay, a shuttle to contain a supply of filling, a detector to indicate non-continuity of the filling when laid, a slide on which the detector is fulcrumed, means mounted on the slide and governed by the detector to effect coöperation of the bunter upon detection of filling failure, said means including a shuttle-feeler, to render the means inoperative if the shuttle is improperly boxed, and means to move the slide to place the detector in position to detect filling failure on each pick toward the replenishing mechanism.

20. In a loom, the lay, a pivotally-mounted and normally inoperative bunter thereon, a shuttle adapted to contain a supply of filling, filling-replenishing mechanism at one side of the loom, a filling-detector, a slide on which it is mounted, a positioning device for the bunter, also mounted on the slide and controlled by the detector, and means to move the slide to operatively position the detector on each shot of the shuttle toward the replenishing mechanism, indication by the detector of filling failure on such pick operating through the positioning device to effect coöperation of the bunter and replenishing mechanism as the lay beats up on the indicated pick.

In testimony whereof I have signed my name to this specification in the presence of two subscribing witnesses.

JONAS NORTHRUP.
